UNITED STATES PATENT OFFICE.

WALES E. VAN AME, OF FORT WAYNE, INDIANA.

AUTOGRAPHIC REGISTER.

SPECIFICATION forming part of Letters Patent No. 639,635, dated December 19, 1899.

Application filed February 9, 1899. Serial No. 705,045. (No model.)

To all whom it may concern:

Be it known that I, WALES E. VAN AME, a citizen of the United States, residing at Fort Wayne, in the county of Allen, in the State of

5 Indiana, have invented certain new and useful Improvements in Autographic Registers; and I do hereby declare that the following is a full, clear, and exact description of the invention, which will enable others skilled in the art 10 to which it appertains to make and use the same, reference being had to the accompanying drawings, which form part of this specification.

My invention relates to improvements in 15 autographic registers in which two records are made at one writing—one for the customer and the other for the cashier or bookkeeper.

The principal objects of my present invention are to provide an improved autographic 20 register specially adapted for use by retail merchants and grocers for the now universal checking system of sales comprising in its construction the greatest degree of simplicity, lightness, compactness, and portability, so 25 arranged as to be easily loaded and readily threaded, requiring neither a tearing-bar nor special tension mechanism nor other operative parts liable to get out of repair, and adapted to feed a manifoldeled or continuous 30 folded sheet over and across a writing-tablet containing a fixed supply of sales-checks, the said manifoldeled sheet being wound or rolled up and remaining in the register until the 35 close of each day's transactions, when it is severed by the bookkeeper for the purpose of auditing and posting, while the customer gets the carbon copy instead of the original, as is usually the practice.

My improvement consists of a containing 40 case or frame of any desired contour, preferably rectangular, and of any proper material possessing the requisite lightness and durability, preferably of wood or aluminium, having a closed chamber or receptacle for the 45 manifoldeled supply-sheet from which it is fed, and provided with a hinged lid for said chamber, affording convenient access thereto, and a roller upon which the portion of said sheet containing a record of each day's transactions 50 is wound up and preserved until it is removed at the close of each day, and suitable mechanism for automatically preventing a retro-

grade movement of said roller when in use, means for guiding said sheet in its passage across said tablet, and means for securing the 55 sales-checks in position.

The principal novel features of my invention are the construction and arrangement whereby great lightness, compactness, and durability are secured, no special tension 60 mechanism is required, and the supply is fed from a manifoldeled sheet to a roll instead of being fed from a roll.

In the accompanying drawings similar reference-numerals indicate like parts in these several views, in which—

Figure 1 is a perspective view of my invention, showing the relative arrangement of the various parts thereof with the manifoldeled sheet and the sales-checks in position thereon. 70 Fig. 2 is a similar perspective of the same with the lid partly raised and broken away at several points to show various features of construction. Fig. 3 is a detail of the roller upon which the record manifoldeled sheet is wound 75 and to which it is fed, showing the longitudinal slot therein and the operating-handle therefor. Fig. 4 is a cross-section of Fig. 1, showing the longitudinal partition.

The case 1, of any desired size, is preferably 80 about six inches in width by about seven and one-half inches in length and about three-fourths of an inch in depth or thickness and weighs but about seven ounces when loaded with two hundred folds of the manifoldeled 85 sheet and fifty sales-checks, thereby making it conveniently portable when in use. The said case 1 is provided with a bottom 17, upright sides 2 and 2', and a hinged lid 3, having a suitable latch or catch 4, and when 90 closed is preferably flush with the upper edge of the adjacent side 2'. This lid 3 is so arranged as to leave a suitable space 3' between the edge thereof and the adjacent side 2' for the passage of the manifoldeled sheet. At a 95 proper distance from said space and parallel therewith is rigidly mounted upon said lid a proper guide 5 for said sheet, preferably consisting of a horizontal wire, whose ends are fixed in said lid, as shown. The opposite sides 100 2 of said frame or casing at their forward end are provided with the integral upright lugs 6, having a suitable perforation, in which the opposite end of the shaft or roller 7 is revo-

lubly mounted. This shaft has upon one extended end a knob 8, which is grasped by the operator in rotating said shaft and has a longitudinal slot 18 to aid in securing the outer 5 end of the manifoldeled sheet, as hereinafter described. This shaft is also provided upon one end and adjacent to the inner face of the corresponding lug 6 with a fixed ratchet-wheel 9, adapted for a holding engagement with a 10 proper pivotal pawl or dog 10. In close proximity to the forward edge of said lid 3 is arranged a transverse rod 11, whose opposite ends are fixed in the said lugs 6, leaving a small space between it and the said lid for the 15 passage of the manifoldeled sheet 12 as it is wound upon the said roller 7, thereby forming a sufficient tension to keep the sheet taut. The said case 1 is also preferably provided with a partition 20, arranged longitudinally 20 of said sheet 12, which serves to keep the folds of said sheet in alinement. The said lid 3 serves as a writing-tablet of greater width than the said manifoldeled sheet 12 to support the projecting or extended end of the 25 sales-checks 13, which are secured in position upon the said lid by means of any suitable fastening at the end thereof adjacent to the latch 4, preferably by means of a wire 14, whose bent ends pass through and are se- 30 cured in said lid, thus making the sales-checks conveniently detachable, as they may be readily torn off from said wire fastener. Upon the extended end of said checks is arranged any desired advertising matter, as that of the 35 firm employing my improvement. Upon the said wire fastener 14 is loosely mounted a thin light plate 15, preferably of aluminium or other sheet metal, for the purpose of separating the underlying sales-checks from the 40 overlying carbon-sheet 16, which is also secured in position upon said wire fastener 14.

The manner of employing my improvement thus described is substantially as follows: The manifoldeled sheet 12, which is preferably 45 ledger-ruled to permit the proper entry of debits and credits in the day's transactions, thereby greatly facilitating the auditing and posting, is placed in the case 1, as shown. The upper free end of said sheet is passed or 50 threaded upward through the said space 3', then through the said guide 5 over and directly above the said carbon-sheet 16 and the sales-checks, then beneath the said rod 11, then over the said shaft or roller 7, to which it is 55 readily secured by passing it through the said slot 18, and then giving it a turn or two upon the roller. The sales-checks and the carbon-sheet are of course previously placed in position upon the lid 3. As fast as the trans- 60 actions of the day are entered upon the said sheet by the sales person it is rolled upon the

said roller, where it is securely preserved until the close of the day's business, when it is torn off by the auditor or bookkeeper by simply passing the point of his pencil transversely 65 of the apparatus through the contracted space between the said rod 11 and the adjacent edge of the said lid 3. The record thus made is readily unrolled and removed from the said roller by disengaging the ratchet mechanism. 70 The entire record of the day's transaction of each sales person is thus preserved upon a single sheet, and the salesman is thus relieved of the duty of auditing the accounts. The record of each transaction will of course be 75 copied at each writing by the said carbon-sheet upon one of the said sales-checks, which is then given to the purchaser. By this means the customer gets the duplicate, while the original remains in the receptacle for the au- 80 ditor. No special tension devices are needed in my improvement, as the slight friction in the space 3' and by the rod 11 is sufficient to keep the sheet perfectly taut when in use. The said ratchet-wheel, with its holding pawl 85 or dog, prevents any retrograde movement of said sheet in use.

My invention thus constructed is very cheap, neat, simple, portable, and convenient, with no operating mechanism having any 90 liability to get out of repair, and conveniently summarizes the entire record of a day's business of each salesman upon one sheet and furnishes the identity of the record of each and every salesman. 95

Having thus described my invention, what I desire to secure by Letters Patent is—

The combination in an autographic register of a casing 1 having a hinged lid therefor provided at its rear end with a slit or space for 100 the passage of the record-sheet; a guide for said sheet fixed upon said lid in close proximity to said space; a roller revolvably mounted in said casing as shown upon which the record-sheet is wound, and provided with a holding mechanism; a transverse rod fixed in said casing in close proximity to said roller for the purpose specified; a manifoldeled sheet arranged in said casing having its outer end se- 105 cured in said roller, and adapted to be led or fed over said lid as described; a series of sales-checks arranged upon said lid beneath said sheet; and means for making a duplicate copy 110 of the entries upon said sheet.

Signed by me at Fort Wayne, Allen county, 115 State of Indiana, this 4th day of February, A. D. 1899.

WALES E. VAN AME.
